UNITED STATES PATENT OFFICE.

JOHN W. LESLIE, OF EVANSTON, ILLINOIS.

REENFORCING GIRTH.

Application filed March 15, 1920. Serial No. 365,952.

To all whom it may concern:

Be it known that I, JOHN W. LESLIE, a citizen of the United States, residing at Evanston, in the county of Cook, State of Illinois, have invented an Improvement in Reenforcing Girths, of which the following is a specification.

This invention relates to reenforcing girths for use in forming joints in metallic 10 tensional box binders, known as "box strap", or the like; and has for its object the production of a girth of simple and economical construction, and having advantages in its application and use hereinafter 15 more specifically pointed out.

In the drawings which constitute merely an illustrative embodiment of the invention:

Fig. 1 is a perspective view, partly in cross section, showing my new reenforcing 20 girth in the process of being applied to mutually overlapped strap ends.

Fig. 2 is a cross sectional view showing the girth as applied to said strap ends, prior to the joint forming operation,

Fig. 3 is a view similar to Fig. 2, showing the girth at a succeeding stage in the joint-forming process,

Fig. 4 is a side view of a joint formed with my reenforcing girth,

Fig. 5 is a plan view of the joint, and Fig. 6 is a cross sectional view on lines 6—6 of Fig. 4.

In the drawings, the two ends of a binder, such as a flat tensional metallic box strap 35 are shown in their relative position when the binder is applied about a box or package, with its ends 1 and 2 overlapped and superposed in alignment. The reenforcing girth herein described is applicable to said 40 overlapped and superposed ends and serves to form an element of a joint whereby said ends are joined together.

The reenforcing girth of my invention 45 comprises a back piece 3, shaped to accord with the upper face of the top strap 2, and of appropriate dimensions, so that the back piece 3 will lie smoothly on and make substantially complete surface contact with said top face. Formed integrally with the back 50 piece 3 are a pair of downwardly and outwardly extending flanges 4; and these flanges are recurved as indicated at 5 to extend upwardly and inwardly (toward the interior surface of the back piece 3), and 55 are preferably prolonged substantially so

that their ends 6 extend inwardly beyond the angles 7 between the back piece 3 and the flanges 4.

It being understood that the reenforcing girth is made preferably of metal and possessed of substantial resiliency, the construction, hereinabove described affords conspicuous advantages in the application of the girth upon the overlapped binder ends and simplifies materially the process of 60 forming a joint therein.

Thus the girth may be made to embrace and maintain itself on the overlapped strap ends, without either threading it successively on the two overlapped strap ends (as 65 would be the case if the girth were formed as a slotted tube as has been a common practice hitherto); or performing bending operations upon the girth in order to cause it to embrace the overlapped strap ends. 75

In the application of my improved girth, it is simply necessary to lay the same on the overlapped strap ends with the flanges down, in the position shown in Figure 1, and subsequently to press downwardly 80 upon it. Whereupon the recurved surfaces 5, camming over the edges of the top strap, will yield; the corners 6 will move downwardly across the longitudinal edges of the overlapped strap ends, and as soon as they 85 are disengaged thereby will snap in behind these edges in the position shown in Figure 2. Thus by a simple operation which can be performed in an instant the girth is applied into embracing relation with the overlapped strap ends and will maintain itself 90 in such relation.

Further important advantages reside in the construction herein presented in that the girth is so formed and its parts have 95 such relation to the strap ends and each other that the girth comes of itself into a substantially tight embracing relation on the strap in the succeeding joint forming operation. As an illustration; in forming 100 a joint of the specific character disclosed in Figures 4, 5, and 6, edgewise crimping is utilized, involving the application of a tool which in effect seizes the girth and enclosed strap at the edges and squeezes these edges 105 inwardly each toward the other. Owing to the contour and arrangement of the flanges 4 and recurved portions thereon 5, it will be apparent that pressure applied inwardly upon the flange 4 will first bend this flange 110

down substantially into contact with the edges of the overlapped strap; and mean-
while the edges 6 will travel inwardly along
the under surface of the bottom strap. It
5 follows that the first part of the joint forming
operation will result in the girth assum-
ing substantially the cross sectional
shape indicated in Figure 3, wherein the
girth completely embraces the strap and lies
10 substantially in flat contact with its surface
to the full extent of the strap area the girth
superimposes. At this stage the situation
is the same as though an open slotted tub-
ular reenforcing girth has been threaded
15 successively onto the two strap ends.

Subsequently a continuation of the edge-
wise crimping operation may be utilized to
produce the joint shown in Figures 4, 5, and
6, wherein conjoint interlocking deforma-
20 tions are produced in the girth and the en-
closed overlapped strap ends; specifically
edgewise crimps in the strap and girth to-
gether. The final stages of the joint forming
25 operation are effected thus in a manner
the same as that familiar where the open
slotted tubular sleeve or girth of the prior
art has been utilized.

It is apparent that it is not necessary to
utilize the specific type of joint-forming
30 operation whose results are shown in Fig-
ures 4, 5, and 6, but that the pressure in-
volved in any crimping or squeezing opera-
tion which squeezes the strap and girth
horizontally or vertically (or both); will
35 result in the girth being forced automatic-
ally into substantially the configurations
shown in Figure 3. Thus not only is the
application of the joint made more simple
40 than hitherto; but the first stage of a strap
joining operation serves also to cause the
girth of my invention substantially to du-
plicate the well known slotted tubular girth
heretofore widely in use.

Having described my invention, I claim:

45 1. As an article of manufacture a sub-
stantially channel-shaped reenforcing girth
for tensional binders having converging
portions adapted to yieldingly engage oppo-
site edges of mutually overlapped strap ends
50 when being applied to both overlapped ends
simultaneously.

2. As an article of manufacture a reen-
forcing girth comprising a back member; a
55 flange adapted to abut one edge of a box
strap; a second flange opposite the first
flange and adapted to yield and recover
when forced over the opposite edge of the
box strap.

3. As an article of manufacture, a reen-
60 forcing girth, comprising a back member;
a flange adapted to engage with an edge of
a box binder; an opposite flange adapted re-
siliently to snap over the opposite edge
when the girth is pressed upon the binder
65 to permit the application of the girth to

two mutually overlapped binder ends si-
multaneously.

4. As an article of manufacture a reen-
forcing girth and seal comprising a back
70 member and opposite flanges said parts be-
ing constructed and arranged so that the
girth is adapted to snap over and into em-
bracing relation with a box strap when ap-
plied thereto in a direction transversely of
75 the face plane of the strap.

5. As an article of manufacture a reen-
forcing girth for box strapping or the like,
comprising a somewhat resilient member
formed with a back piece, and opposite flanges
80 adapted to be wedged apart as the girth is
applied to a box strap in a direction oblique
to its length, and to snap in behind the
outer edge of the face of the strap remote
from the direction of application of the
85 girth.

6. As an article of manufacture a reen-
forcing girth for box strapping or the like
comprising a somewhat resilient member
formed with a back piece adapted to con-
90 tact with a surface of the box strap, and a
pair of opposite flanges extending substan-
tially outwardly from the back piece and
having recurved portions extending in-
wardly beyond the edges of the back piece;
95 to provide a girth which may be sprung or
snapped into place on two superposed strap
lengths simultaneously.

7. As an article of manufacture a reen-
forcing girth for box strapping or the like
comprising a somewhat resilient member 100
formed with a back piece adapted to con-
tact with a surface of the box strap, and a
pair of opposite flanges extending substan-
tially outwardly from the back piece and
having recurved portions extending in-
105 wardly beyond the edges of the back piece,
said recurved portions sloping on their ex-
posed faces toward the back piece.

8. As an article of manufacture a reen-
forcing girth for box binders or the like 110
comprising a somewhat resilient member
formed with a back piece adapted to contact
with a surface of the binder, and a pair of
opposite flanges extending substantially out-
wardly from the back piece and having re-
115 curved portions extending inwardly beyond
the edges of the back piece, said flanges and
recurved portions being adapted to straighten
out and come into substantially flat con-
tacting relation with the surface of the 120
binder under tension on a box when the
girth and encased strap are forcibly com-
pressed.

9. The method of forming a joint in ten-
sional box binders or the like, which con-
125 sists in applying to the overlapped ends of
said binders a reenforcing girth loosely em-
bracing said ends and having parts project-
ing over both faces thereof; squeezing said
girth into substantially complete surface en-
130

gagement with the binder ends throughout the inner area of the girth, and forming interlocking distortions simultaneously in the joint and the binder ends by a continuous 5 squeezing operation.

10. The method of forming a joint in flat metallic binders or the like, which consists in applying to the superposed portions of said binders a reinforcing girth loosely fitting upon said superposed portions, then squeezing the girth into strap end embracing relationship, and forming a joint involving the girth and the ends by a continuation of the squeezing operation.

15. 11. As an article of manufacture, a somewhat resilient sheet metal reenforcing girth adapted to serve as an element of a box strap joint, and comprising in combination a back piece, adapted to be applied to the 20 outer surface of a box strap on a box or the like; a flange thereon adapted to partly underlie and loosely fit upon the under surface of said box strap, said part being so constructed and arranged that the compression of said girth on the strap is adapted to

bend said flange portion into a snug contact with the under surface of the strap.

12. As an article of manufacture, a reinforcing girth adapted to serve as an element of a box strap joint and comprising 30 in combination a back piece, adapted to be applied to the outer surface of a box strap on a box or the like; a flange integral with one longitudinal edge of the back piece, and extending first outwardly therefrom and 35 then inwardly, and having a curved cross sectional contour on its inwardly extending portion, whereby an inner edge is provided, adapted to contact first with the lower surface of the strap and move inwardly there- 40 upon under the compression of the girth in the crimping operation, to straighten out said flange and bring the same into substantially complete superficial contact with the strap surfaces in the first part of the crimp- 45 ing operation incident to forming a joint.

In testimony whereof, I have signed my name to this specification.

JOHN W. LESLIE.
